UNITED STATES PATENT OFFICE.

WILLIAM HENRY WETZEL, OF ABERDEEN, WASHINGTON, ASSIGNOR OF TWO-FIFTHS
TO DWIGHT OTHNIEL MOODY, OF ABERDEEN, WASHINGTON.

DOUBLE-HEADED THREE-WAY SIGNAL LIGHT.

Application filed July 9, 1923. Serial No. 650,567.

This invention relates to a signal and particularly to means indicating the direction of travel of automobiles or the like.

An important object of the invention is to provide a signal of this character which is simple in construction, durable, and can be manufactured at a comparatively low cost.

A further object of the invention is the provision of a signal which can be seen from the front or rear of the vehicle upon which it is mounted and also operate as a stop light.

A still further object of the invention is the provision of a signal of this character which can be readily seen for comparatively long distances without providing an unduly large structure.

Other objects and advantages of this invention will be apparent during the course of the following description.

In the accompanying drawings forming a part of this specification and in which like numerals are employed to designate like parts throughout the same:

Figure 1 is a perspective view of my improved device,

Figure 2 is a cross section taken therethrough,

Figure 3 is a horizontal section taken on line 3—3 of Figure 2,

Figure 4 is a perspective view of the light shield, and

Figure 5 is a perspective view of a portion of the casing arranged within the device.

In the drawings, wherein for the purpose of illustration is shown the preferred embodiment of my invention, the numeral 10 generally indicates the outer casing of my improved signal, this casing being substantially oval shape in cross section and constructed of comparatively thin yet durable metal. The casing 10 is closed at each end by a plate 11, each having an indicia opening in the shape of a double headed arrow, the heads being designated by the numeral 12 and the connecting stem by the numeral 13.

Mounted in the oval shaped casing 10 is a substantially U-shaped frame 14, which extends between the opposite end plates 11 and 14 is provided with a cover 15 engaging over the upper edges of the opposite side portions of said U-shaped frame, forming an inner casing. Mounted on the light or connecting portion of the U-shaped frame 14 approximately at the center thereof is an angled

member 16, to the opposite ends of which are attached electric light sockets 17 for receiving electric bulbs 18. It will be noted by referring to Figures 2 and 3 that the electric light bulbs are arranged approximately midway of the length of the U-shaped structure and slightly spaced inwardly from the opposite side portions thereof. It is also to be noted that the lights are arranged in alignment with said arrowheads of the indicia openings in the end walls of the casing, the purpose of which will be set forth as the description proceeds.

Arranged within the inner casing formed by the U-shaped frame 14 and cover 15 is a substantially inverted U-shaped frame 19, which also extends to both end plates 11 of the casing. The opposite side portions of the inverted U-shaped frame 19 are in alignment with the electric light bulbs 18 respectively and the inner ends of the arrowheads with the stem of the double headed arrow-shaped indicia extending between said side portions of the frame. The said side portions of the inverted U-shaped frame form partitions and are split intermediate their ends to provide offset portions or shields 20 extending inwardly of said partitions and downwardly, as clearly shown in Figures 2 and 4 of the drawings. By stamping out the partitions to form the shields it provides for locating the electric light bulbs in alignment with the opposite end portions of said portions, the shields extending downwardly at angles between the electric light bulbs to prevent light rays from one bulb being reflected through the small opening provided for receiving the other bulb, as clearly shown in Figures 2 and 3 of the official drawings.

The shield 20 adjacent the lamp that is lighted will act as a shield and prevent light rays from shining through the small opening in the opposite partition or side portion of the inverted U-shaped structure which receives the other bulb, and likewise the opposite partition of the inverted U-shaped frame will prevent light rays from passing through the arrowhead opening at the opposite side of the casing from the lighted electric lamp. It will be clear therefore that when either lamp is lighted it will not only light the arrowheads on a line therewith at opposite ends of the casing 10 but will also light the stem for its entire length, as indicated in Fig. 3, the op-

posite partition 19 and shield 20 cooperating therewith preventing the light from shining through the opposite arrowheads. In this manner an arrow pointing in either direction 5 at both ends of the casing can be shown according to direction to be indicated by lighting one of the lamps, and the double headed arrows shown by lighting both lamps.

It is to be understood that the form of my 10 invention herein shown and described is to be taken as the preferred example of the same, and that various changes as to the shape, size, and arrangement of parts may be resorted to, without departing from the spirit of the invention, or the scope of the subjoined claim.

Any approved means may be employed for holding the glass plates 11 at the ends of the outer casing in place, as for instance a flanged ring 25 at each end of the casing secured to 20 the sides of the latter by screws 26, said rings clamping the glass plates against the ends of the casing as shown in the drawings.

Having thus described my invention, what I claim as new is:

A direction signal device for automobiles comprising a casing having indicia openings in its opposite ends, each opening being in the shape of a double headed arrow, an inner casing of approximately the same size as the indicia openings in the ends of the casing and 35 cooperating with said ends, spaced apart partitions extending between the ends of the casing in alignment with the inner ends of the arrowheads, respectively, and having intermediate openings through the same, shields spaced from said openings at the inner sides thereof, and electric lamps located in the openings in the partitions whereby light from either lamp will be projected at opposite sides 40 of the partition in which the lamp is located and through the opposite arrowheads at one side of said partition as well as the stem at the other side of the partition.

WILLIAM HENRY WETZEL.
